US0D1072488S

(12) **United States Design Patent** (10) **Patent No.:** **US D1,072,488 S**
(45) **Date of Patent:** **** Apr. 29, 2025**

(54) **LID FOR STORAGE BOX**

(71) Applicant: **L&F PLASTICS, CO., LTD.**, Miaoli County (TW)

(72) Inventor: **Mu-Chuan Hsu**, Miaoli County (TW)

(73) Assignee: **L&F PLASTICS, CO., LTD.**, Miaoli County (TW)

(**) Term: **15 Years**

(21) Appl. No.: **29/862,650**

(22) Filed: **Dec. 12, 2022**

(30) **Foreign Application Priority Data**

Jun. 23, 2022 (TW) 111303085
